UNITED STATES PATENT OFFICE.

CHARLES H. METZ, OF WALTHAM, MASSACHUSETTS.

DESIGN FOR A BICYCLE HANDLE-BAR EXTENSION.

SPECIFICATION forming part of Design No. 31,007, dated June 13, 1899.

Application filed May 11, 1899. Serial No. 716,440. Term of patent 7 years.

To all whom it may concern:

Be it known that I, CHARLES H. METZ, of Waltham, in the county of Middlesex and State of Massachusetts, have invented and 5 produced a new and original Design for Bicycle Handle-Bar Extensions, of which the following is a specification, reference being had to the accompanying drawing, forming part thereof.

10 The drawing represents a perspective view of a bicycle handle-bar extension illustrating my new design.

15 The leading features of the new design for bicycle handle-bar extensions consist in the design as herein shown and described.

As shown in the drawing, the cylindrical portion 5 has the convex upper end 6, slightly below which end is the laterally-extending and downwardly-inclined member 7, having the transverse collar 8, from the opposite side 20 of which extends the perforated hub 9.

What I claim is—

The design for a bicycle handle-bar extension as herein shown and described.

CHARLES H. METZ.
